COVER OR LID LATCH

Herbert M. Piker, Wyoming, and William L. Schultz, Hamilton, Ohio, assignors to The Hamilton Metal Products Company, Hamilton, Ohio, a corporation of Ohio

Application March 12, 1949, Serial No. 81,166

6 Claims. (Cl. 220—55)

1

This invention relates to improvements in a spring latch for a hingedly mounted cover or lid such as used, for example, on minnow buckets.

The use of hinged lids or covers on buckets, such as minnow buckets, and other types of containers and which lids and covers have spring latches for releasably locking the lids or covers in closed position is old and well known. In the past, the said latches were awkward to manipulate and handle requiring the holding of the bucket or container while the spring latch was being released. By the present invention these difficulties are eliminated thereby resulting in a better minnow bucket than was heretofore known or used.

It is, therefore, the principal object of the present invention to provide a latch or a hingedly mounted lid or cover that can be released with the least amount of difficulty.

Another object of this invention is the provision of a latch for a hinged lid or cover that can be released without the necessity of holding the bucket or container during the releasing of the latch whereupon the lid or cover may be actuated about its hinged connection.

A further object of this invention is the provision of a latch for a hinged lid or cover that can be released with one hand and used while in the hand as a means for actuating the cover or lid about its hinge.

A still further object of this invention is the provision of a latch that will accomplish the foregoing objects that is extremely simple in construction, economical to produce and readily operable.

Other objects and advantages of the present invention should be readily apparent by reference to the following specification considered in conjunction with the accompanying drawings forming a part thereof and it is to be understood that any modifications may be made in the exact structural details there shown and described, within the scope of the appended claims, without departing from or exceeding the spirit of the invention.

In the drawings:

Fig. 1 is a side elevation of a minnow bucket or container embodying the latch of the present invention.

Fig. 2 is a top plan view of the minnow bucket of Fig. 1.

Fig. 3 is a fragmentary enlarged sectional view through the upper end of the bucket as seen from line 3—3 on Fig. 2.

Fig. 4 is a fragmentary sectional view of the

2

bucket showing certain of the parts of Fig. 3 in a second operative position.

Fig. 5 is a perspective view of the latch, per se, of the present invention.

Throughout the several views of the drawings similar reference characters are employed to denote the same or similar parts.

As was noted above, this invention pertains generally to a spring type of latch for yieldingly retaining in closed position a lid or cover for a container and is illustrated in the drawings and will be described in connection with a minnow bucket, but it is to be understood that the invention is not limited to minnow buckets except as so done in the claims.

Specifically, the minnow bucket illustrated in the drawings comprises a cylindrical body portion 10 to which is attached a bottom 11 in any suitable or desirable manner, preferably in the manner that the top 12 is attached as will presently be described. The minnow bucket, per se, is generally associated with an outer container in which water or the like is present and enters the minnow bucket through holes or apertures 13, through the bucket body 10, near or at the bottom 11 thereof.

As illustrated in Fig. 3, the top 12 is connected with the upper end of the bucket body 10 by means of, what is known in the trade as, a double seam which consists in forming the perimeter of the cover 12 substantially as a hook 14 to be inter-engaged with a complementary hook 15 at the upper end of the bucket body 10. In forming a water-proof joint there is provided a gasket between the inter-engaged hook portions 14 and 15, the said gasket not being shown in the drawings. After the said hook portions 14 and 15 are inter-engaged they are subjected to pressure for securing the parts to one another. As shown in the drawing, the top 12 is illustrated as depressed thereby providing on the said top 12 an upstanding peripheral flange 16 which, in effect, provides a dish or tray at the top of the minnow bucket, which may be used to retain ice to supply cooling water to the minnow bucket and minnows therein during transportation in hot weather or for other reasons.

The top 12 is provided centrally with a large opening 17 and has the free edge of the opening turned on itself as at 18 to thereby avoid a sharp edge to said opening and at the same time provide a rim for cooperation with a closing lid or cover. It should be understood that this particular formation of turning the flange 18 on itself is a matter of choice as this edge may be

beaded or have the flange turned into the bucket and beneath the top 12.

The opening 17 is adapted to be closed by a lid or cover 19 of an area somewhat greater than the area of the opening with the perimeter of the lid or cover downwardly turned as at 20 to engage the opening rim or flange 18. Centrally of the lid or cover 19 it may be formed with depressions to provide angularly related reinforcing ribs 21 conveniently employed to have formed therethrough apertures 22 for supplying air to the interior of the container and, when the bucket top 12 is used as an ice tray, to permit the melted ice or water to be discharged into the bucket.

Any suitable or desirable means may be employed for hingedly connecting the lid or cover 19 to the bucket top 12, that shown in the drawing comprising a hinge lug 23 soldered, welded or otherwise secured to the bucket top 12 and having a hinge eye 24 at its inner end. It will be understood that the hinge eye 24 may be struck from the bucket top 12 as is frequently the practice. Aligned with the hinged lug eye 24 are hinge eyes 25 and 26 at the outer ends of lugs 27 and 28 integral with and outwardly projecting from the lid or cover 19 at one point thereof. Extending through the aligned hinge eyes 24, 25, and 26 is a hinge pin 27 and by reference to Figs. 2 and 3, it will be readily understood that the said lid or cover 19 may be actuated in a counter-clockwise direction about the hinge pin 27.

The said lid or cover 19 is retained in its closed position by a yieldable or spring latch indicated in its entirety by the reference character 28' illustrated in vertical section in Figs. 3 and 4 and in perspective in Fig. 5.

The latch 28' is made of a length of tempered spring material and comprises a base portion 29 through which is formed an aperture 30. Upstanding at the inner end of the base portion 29 is a portion 31 hereinafter referred to as a post. The upper end of the post 31 is turned on itself as at 32 for the purpose of providing a comfortable grip and for the purpose of reinforcing the post 31 transversely thereof. At the other end of the base 29 is an outwardly, downwardly, inclining portion or finger 33 joined through a rounded fillet 34 with a spring finger 35 which outwardly, upwardly, inclines substantially opposite to the inclination of the finger 33. The spring finger 35 terminates in the latching nose 36 having thereafter an upwardly, inwardly, inclining latching cam 37 from which rises the actuating arm 38. The actuating arm 38 and the post 31 are normally parallel to one another as shown in Fig. 3 with the arm 38 having its upper end turned on itself as at 39 to be in opposition to the post turned portion 32.

In practice the latch 28' is mounted on the lid or cover 19 as illustrated in Fig. 3 by passing the post 31 and arm 38, respectively, through an aperture 40 and 41 in the cover or lid at points diametrically across from the bucket top hinge lug 23 and with the base 29 of the latch in face contact with the under surface of the cover or lid 19 immediately outwardly of the aperture 40. The said lid or cover 19 is provided with an aperture 42 to be aligned with the aperture 30 in the latch base 29 and extending through said aligned apertures 42 and 30 is a rivet 43 which has its opposite ends upset, as rivet heads, for securing the latch 28 in position.

In order to transport the bucket use is made of a bail handle 44 which has its opposite ends

pivotally disposed in suitable eyes 45 and 46 whereby said bail handle 44 may be actuated from the carrying position of Fig. 1 to its normal position in Fig. 2.

The operation of the spring latch of the present invention is believed obvious from the disclosure in Figs. 3 and 4 which, however, is briefly as follows:

With the parts in their normal positions as illustrated in Fig. 3 and the user desiring to gain access to the interior of the minnow bucket, he would grasp the portions 32, of the post 31, and 39, of the arm 38, between his thumb and a finger of either hand and exert a slight pressure for thereby 10 inwardly actuating the arm 38, latching cam 37, latching nose 36, and spring finger 35 on the fillet 34 toward the post 31. In other words, this would cause the spring latch 28 to be deformed from its normal position in Fig. 3 to the position in Fig. 4 and thereby bring the latching nose 36 within the bucket top opening 17 or inwardly of the flange 18. The user would then immediately exert an upward 15 lifting force on the latch for thereby actuating the cover or lid 19 about the hinge pin 27. It will be noted that this operation is readily performed without the necessity of holding the bucket, or any part thereof, as no lateral force of any nature is being exerted on the bucket or its lid or cover 19 thereby tending to in any wise laterally 20 displace the bucket as a whole and since in actuating the lid or cover about the hinge pin 27 no lateral force is necessary but merely an upward or lifting force the said cover or lid 19 may be opened without holding the bucket or any part 25 thereof.

In order to relatch the lid or cover 19 it is only necessary to allow the said lid or cover to close itself by its own weight since at this time the latch 28 will be in the normal position illustrated 30 in Fig. 3 causing the inner edge of the opening 17, or the flange 18, to engage with the upwardly, outwardly, inclined spring finger 35 which will act as a cam in forcing the latching nose 36 to the position of Fig. 4 until said latching nose 35 is below the flange 18, or opening edge, whereupon the inherent spring in the latch will cause the locking cam 37 to engage with the lower edge of the opening 17 and return the latch to its normal position from Fig. 4 to Fig. 3 and thereby 40 again yieldingly close and latch the lid or cover 50 19 in closed position.

In view of the foregoing, it is believed now evident that there has been provided a spring latch for a hinged lid or cover for a container which 55 will accomplish the objects initially set forth above.

What is claimed is:

1. A latch of the class described formed from a single piece of spring material comprising a base portion, a post at one end of the base portion and upstanding substantially normal to the base portion, a spring arm at the other end of the base portion and projecting below the base portion, a latching nose carried by the spring arm and yieldingly retained in normal latching position by said spring arm, and means manually operable toward said post upon engagement of the means and post for releasing the latching nose.

2. A latch of the class described formed from a single piece of spring material comprising a base portion, a post at one end of the base portion and upstanding substantially normal to the base portion, a spring arm at the other end of the base portion and projecting below the base

portion, a latching nose carried by the spring arm and yieldingly retained in normal latching position by said spring arm, and means manually operable toward said post upon engagement of the means and post for releasing the latching nose, including a finger piece upstanding with respect to the base portion with said post and finger piece spaced from one another for simultaneous engagement by the fingers of one hand for actuating the said finger piece toward the said post.

3. A latch of the class described formed from a single piece of spring material comprising a base portion, a post at one end of the base portion and upstanding substantially normal to the base portion, a spring arm at the other end of the base portion and projecting below the base portion, a latching nose carried by the spring arm and yieldingly retained in normal latching position by said spring arm, means manually operable toward said post upon engagement of the means and post for releasing the latching nose, including a finger piece upstanding with respect to the base portion with said post and finger piece spaced from one another for simultaneous engagement by the fingers of one hand for actuating the said finger piece toward the said post, and cam means between said latching nose and spring arm and between said latching nose and finger piece for respectively retracting the latching nose and for actuating same to a fully latched position.

4. In a device of the class described the combination with a container top having an opening therethrough and a cover hingedly carried by said container top for movement toward and from the container top, said cover being of an area somewhat greater than the area of said opening whereby the cover overlaps the opening edge, of a one piece latch including a base secured to the undersurface of the cover, a spring finger at one end of and extending downwardly from the base, a latching nose at the end of the spring finger underlying the top opening edge when the cover is closed, a post from the other end of the base projecting through the cover to a point thereabove, and manually actuatable means projecting from the latch nose through the cover to a point thereabove, said manually actuatable means and post being positioned with respect to one another for simultaneous engagement and actuation toward one another by the fingers of one hand for retracting the latching nose from its latching position and act as means for the actuation of the cover about its hinge.

5. In a device of the class described the combination with a container top having an opening therethrough and a cover hingedly carried by said container top for movement toward and from the container top, said cover being of an area somewhat greater than the area of said opening whereby the cover overlaps the opening edge, of a one piece latch including a base secured to the undersurface of the cover, a

spring finger at one end of and extending downwardly from the base, a latching nose at the end of the spring finger underlying the top opening edge when the cover is closed, a post from the other end of the base projecting through the cover to a point thereabove, and manually actuatable means projecting from the latch nose through the cover to a point thereabove, said manually actuatable means and post being positioned with respect to one another for simultaneous engagement and actuation toward one another by the fingers of one hand for retracting the latching nose from its latching position and act as means for the actuation of the cover about its hinge, said nose retracting means including a finger piece.

6. In a device of the class described the combination with a container top having an opening therethrough and a cover hingedly carried by said container top for movement toward and from the container top, said cover being of an area somewhat greater than the area of said opening whereby the cover overlaps the opening edge, of a one piece latch including a base secured to the undersurface of the cover, a spring finger at one end of and extending downwardly from the base, a latching nose at the end of the spring finger underlying the top opening edge when the cover is closed, a post from the other end of the base projecting through the cover to a point thereabove, and manually actuatable means projecting from the latch nose through the cover to a point thereabove, said manually actuatable means and post being positioned with respect to one another for simultaneous engagement and actuation toward one another by the fingers of one hand for retracting the latching nose from its latching position and act as means for the actuation of the cover about its hinge, said nose retracting means including a finger piece, said spring finger inclining in a direction away from the latching nose to act as a cam upon engagement with the top opening edge during the closing of the cover, and cam means between the latching nose and finger piece for engagement with the edge of the top opening for effecting the final closing of the cover upon actuation of the locking nose to its locking position by the spring finger.
